CLAIM

The ornamental design for a baseball swing-training device,
as shown and described.

DESCRIPTION

FIG. 1 is a perspective view of a baseball swing-training device showing my new design;

FIG. 2 is a front elevational view;

FIG. 3 is a rear elevational view;

FIG. 4 is a side elevational view, the other side of which
being a mirror image;

FIG. 5 is a top plan view;

FIG. 6 is a bottom plan view; and,

FIG. 7 is a reduced perspective view thereof.

The broken line showing of the batter in FIG. 7 is for
illustrative purposes only and forms no part of the claimed
design.
